UNITED STATES PATENT OFFICE

FRANK E. RUDD, OF LOUISVILLE, KENTUCKY

DESIGN FOR TEXTILE FABRIC

Application filed May 19, 1930. Serial No. 35,680. Term of patent 3½ years.

To all whom it may concern:

Be it known that I, FRANK E. RUDD, a citizen of the United States, and a resident of Louisville, Kentucky, have invented a new, original, and ornamental Design for Textile Fabric, of which the following is a specification, reference being had to the accompanying drawing, forming part hereof, in which is shown a plan view of a piece of textile fabric embodying my design. This design consists of a border or selvage decoration indicated at A and a body portion which is the characteristic feature of my design, indicated at B, the body portion extending to the border or selvage decoration of the opposite selvage edge of the fabric.

I claim:

The ornamental design for textile fabric, substantially as illustrated and described.

In testimony whereof, I have signed my name to this specification this 13th day of May, 1930.

FRANK E. RUDD.
